UNITED STATES PATENT OFFICE.

THEODORUS H. NAKKEN, OF JERSEY CITY, NEW JERSEY, ASSIGNOR TO SAMUEL BUT-
TENBERG AND MEYER NATHAN LEIBOWITZ, OF NEW YORK, N. Y.

ELECTROMAGNETIC VIBRATING DEVICE.

Application filed May 3, 1926. Serial No. 106,372.

This invention relates to electromagnetic devices for effecting vibrations in accordance with variations of an electric current.

Mechanisms of this kind for effecting the vibration of a single member, such as a diaphragm of a telephone receiver or of a loud speaker for wireless telephony, are well known, and comprise, for instance, an armature pivotally mounted between double pole pieces of a magnet, such armature either being associated with a coil, through which the electric current flows, in which case the magnet is of the permanent variety, or being in the form of a permanent magnet, in which case the magnet, between the pole pieces of which such armature is mounted, is associated with a coil through which the electric current flows, so that the magnetization thereof will vary according to the variation in the strength of the current.

The object of the present invention is to provide a device of this kind which is especially adapted for imparting vibrations to a plurality of members, such as, for instance, the cone of a loud speaker for wireless receivers or the like, and the diaphragm of a horn which may be combined in a single unit with such cone.

This application of the device, however, is given merely by way of example, since the device could be used for other purposes than operating two diaphragms associated together in a loud speaker.

The device, according to the present invention, comprises a plurality of pivoted armatures extending between the poles of a magnet, and a coil or coils connected in the circuit of said electric current, associated with such device, and adapted to control the magnetic interaction between the armatures and the poles of the magnet.

In order that the invention may be clearly understood, reference is made to the accompanying drawings which illustrate by way of example, three embodiments of my invention, and in which:—

Figure 1 is a diagrammatic view in elevation of one form of the device;

Figure 2 is a diagrammatic view in plan of the armatures of this device;

Figure 3 is a diagrammatic view in elevation of a modified form of the device;

Figure 4 is a diagrammatic view in elevation of a further modified form of the device;

Figure 5 is a plan view of a preferred form of the invention;

Figure 6 is a front elevation of this form; and

Figure 7 is a sectional elevation taken on line VII—VII of Figure 6.

Referring to Figures 1 and 2 of the drawings, *a* is a magnet which may be an electromagnet excited by a constant current, or a permanent magnet. The poles of this magnet, as clearly shown in Figure 1, are bifurcated, thereby forming two upper poles *b*¹, *b*², of one polarity, and two lower poles *c*¹, *c*², of the other polarity. Two armatures *d*¹, *d*², are floatingly held side by side between the poles of the magnet, with their ends extending respectively between the pole pieces *b*¹, *c*¹, and *b*², *c*². The mounting of the two armatures preferably comprises a flat spring *e* extending transversely of the armatures and attached to them in any suitable manner intermediate their ends. The ends of the flat spring *e* are anchored in any suitable manner, but preferably in a bobbin *f* or the like, surrounding the centre portions of the two armatures, and upon which is wound a coil *g* through which the variable electric current is adapted to flow.

The two armatures extend longitudinally side by side, but are separated from each other a slight distance, so that there will be no frictional contact between them. One end of each armature extends beyond the pole pieces, and to such extensions are connected rods *h*¹, *h*², which are also connected respectively to the members to which vibrations are adapted to be imparted. The rods or the like *h*¹, *h*², may be connected respectively at opposite sides of the device or at the same side of the device.

When the varying current flows through the coil *g*, the armatures *d*¹, *d*², will be magnetized, the magnetization thereof varying according to the strength of the current. Owing to the variation in the magnetization of the armatures, interaction between the ends thereof extending between the pole pieces will vary, and the armatures will vibrate in accordance with the variations in the strength of the current flowing through the coil *g*.

These vibrations will be transmitted by means of the rods h^1 , h^2 , to the members which are to be vibrated.

Referring to Figure 3 of the drawings, the 5 two armatures d^1 , d^2 , illustrated therein, are mounted end to end instead of side by side, and their ends extend between the triple pole pieces of the poles of the magnet a . In such a construction, of course, each armature is 10 mounted upon a separate spring e^1 , e^2 , and each is influenced by a separate coil g^1 , g^2 , which may be connected in series or parallel.

Figure 4 illustrates a further development 15 of the idea embodied in Figure 3. In the construction according to this figure, the central pole pieces b^3 , c^3 , of the construction according to Figure 3 are substituted by double pole pieces b^4 , b^5 , and c^4 , c^5 . Otherwise, the two constructions are the same.

20 The construction illustrated in Figures 5 to 7 of the drawings is substantially the same as that illustrated in Figures 1 and 2 of the drawing, but in this construction the parts have been assembled in a more compact form.

25 As clearly shown in these figures, the armatures d^1 , d^2 are pivotally mounted between the poles of the permanent magnet by being connected to the spring e , which is anchored at its ends, preferably as in the former construction, in the bobbin f upon which the coil g is wound. The rods h^1 , h^2 , are connected 30 respectively to the armatures d^1 , d^2 , on the same side of the device. The permanent magnet a comprises the two pairs of pole pieces b^1 , b^2 , and c^1 , c^2 , extending respectively downwardly and upwardly from the bridge pieces k , l , which extend in opposite directions, and are connected to the yoke m . Such magnet 35 may be formed of a single casting, or the 40 bridge pieces, with the pole pieces extending therefrom, may be bolted to the yoke piece m , or connected thereto in any other suitable manner.

45 By providing two diaphragms which can move independently of each other, the two members to be vibrated will be actuated without the vibrations of one member affecting the vibrations of the other. This would not be the case if the two members were connected 50 to the opposite ends of a single armature, since, with such a construction, there would necessarily be interaction between the two members, owing to their direct connection with each other through the armature; and, 55 consequently, each of such members would not have a separate natural period of vibration, but the combined unit would have a natural period of vibration, depending upon the individual natural periods of vibration.

60 The construction according to the present invention entirely overcomes this disadvantage, since the two members being allowed to vibrate independently of each other, the natural period of vibration of each will not be effected. Consequently, if the device were

used for operating the diaphragm of a horn and the cone of a loud speaker combined in a single unit, the diaphragm and the cone would each be vibrated without the one acting as a load upon the other, and each would 70 retain its normal characteristics.

As previously stated, however, the invention could be used for other purposes than the operation of the diaphragm of a horn and the cone of a loud speaker combined in a 75 single unit.

The armatures, instead of being pivotally mounted intermediate their ends, may have their forward ends extending between the two poles of a magnet, and be pivotally 80 mounted at their rear ends, such armatures being floatingly held in an intermediate position between the poles by springs or the like, or by being themselves of resilient material and having their rear ends anchored. 85

It is also obvious that further modification of the forms illustrated may be devised without departing from the spirit and scope of the invention as defined in the accompanying claims. 90

I claim—

1. An electromagnetic device for effecting vibrations in a plurality of members in accordance with variations in an electric current comprising a plurality of armatures 95 floatingly mounted between the poles of a magnet, a single member to which both of such armatures are connected and by which they are floatingly supported between said poles, and means associated with the circuit of said 100 electric current and associated with such device adapted to control the magnetic interaction between the armatures and the poles of the magnet.

2. An electromagnetic device for effecting vibrations in a plurality of members in accordance with variations in an electric current, comprising a magnet having opposed poles, a plurality of armatures extending side by side and floatingly mounted between said 110 poles, means for floatingly supporting such armatures between such poles and means associated with the circuit of said current and associated with such device adapted to control the magnetic interaction between the 115 armatures and the poles of the magnet.

3. An electromagnetic device for effecting vibrations in a plurality of members in accordance with variations in an electric current, comprising a plurality of armatures extending side by side, means for connecting said armatures to said members, a magnet having opposed poles between which the armatures are floatingly supported, means for floatingly supporting said armatures between said poles, and means for magnetizing said armatures by said electric current whereby the magnetization thereof will vary in accordance with the variations in the electric current. 120 125 130

4. An electromagnetic device for effecting vibrations in a plurality of members in accordance with vibrations in an electric current, comprising a magnet having each pole divided into two pole pieces, a plurality of armatures extending side by side, floatingly mounted between the poles of the magnet, with their ends extending between the opposed pole pieces, means for floatingly supporting such armatures between such pole pieces, and means for magnetizing said armatures in accordance with the variations in said electric current.
5. An electromagnetic device for effecting vibrations in a plurality of members in accordance with vibrations in an electric current, comprising a magnet having each pole divided into two pole pieces, a plurality of armatures mounted upon a spring extending transversely of the armatures, and having its ends fixedly supported, such armatures extending side by side with their ends extend-
- ing between the opposed pole pieces, and means for magnetizing said armatures in accordance with the variations in said electric current.
6. An electromagnetic device for effecting vibrations in a plurality of members in accordance with vibrations in an electric current, comprising a magnet having opposed poles, each of which is divided into two pole pieces, a plurality of armatures extending side by side mounted upon a flat spring extending transversely thereof, and having its ends anchored, such armatures having their ends extending respectively between the opposed pole pieces of said magnet, and means associated with the circuit of said electric current and associated with such device, adapted to control the magnetic interaction between said armatures and said pole pieces.

In testimony whereof I affix my signature.

THEODORUS H. NAKKEN.
